UNITED STATES PATENT OFFICE

RICHARD G. KNOWLAND, OF WOLLASTON, AND NATHANIEL KOSAK, OF EVERETT,
MASSACHUSETTS, ASSIGNORS TO NASHUA MANUFACTURING COMPANY, OF NASHUA,
NEW HAMPSHIRE, A CORPORATION OF NEW HAMPSHIRE

DYE BATH AND PROCESS OF DYEING

No Drawing.

Application filed March 12, 1928. Serial No. 261,178.

This invention relates to vat dye baths and processes of vat dyeing fabrics, yarn, or fibre, all of which will be hereinafter included in the term "fabrics" or "goods."

5 In the usual processes of vat dyeing it is necessary to apply the dye to the fabrics in a reduced condition and in an alkaline solution in order to make the dye adhere to the fibre of the goods. In a typical process the dye is 10 reduced by sodium hyposulphite and is applied to the goods in a caustic soda solution. After the fabric has been run through the dye bath it is, in a typical process, washed with water, the dye is then oxidized, an agent such 15 as sodium perborate or potassium bichromate being commonly used for this purpose, the goods are again washed, given the usual soaping treatment, and then given a final washing and drying.

20 The present invention aims to improve vat dye baths and processes of vat dyeing with a view to reducing the handling of the goods and the treatments required after the dyeing operation per se has been performed.

25 We have discovered that this result can be realized by substituting for the caustic soda ordinarily used in preparing the dye bath, an alkaline material which will break up upon the subsequent drying of the goods into constituents that have no harmful effect on the goods and which preferably are volatile in nature so that they can be driven out of the goods during the drying step. The quarternary ammonium bases such as tetramethylammonium hydroxide or tetramethylammonium hydroxide are particularly satisfactory 30 for this purpose.

The vat dye bath can be prepared in the usual way, the dye being reduced by sodium hydrosulphite or any other suitable reducing agent in a solution which is given the desired degree of alkalinity by the addition thereto of a suitable quantity of either of the ammonium bases above mentioned. A formula suitable for laboratory purposes is as 40 follows:

0.4 gms. indanthrene blue GCD (color index number 1113).

1.6 gms. sodium hydrosulphite.

50 290.0 cc. tetramethylammonium hydroxide

solution containing 15.7 gms. per liter, the whole made up to 600 c.

The same proportions can be used in preparing a bath for mill dyeing. It will be understood, however, that the proportions of the ingredients may be varied in accordance with the nature of the dye used, the results desired, and other practical considerations, the foregoing formula serving simply as an example.

60 The dyeing operation may be performed in the usual manner, no change in the usual practice being required because of the use of quarternary ammonium bases. As the fabric emerges from the dye bath it is run between rollers to squeeze out the surplus color and is then dried. Ordinarily the drying operation is performed by running the fabric over a so-called "can dryer." It is obvious 65 that the goods can be washed if desired but washing is not necessary. They can also be treated with oxidizing agents if desired, and in some cases such treatment is preferable. Usually, however, an entirely satisfactory 70 oxidation of the dye takes place during the 75 drying operation.

The step of drying the goods ordinarily is conducted under a moderate heat, a temperature of at least 60° C. being maintained, and such a temperature is sufficient to break up 80 the quarternary ammonium base into volatile constituents which are driven out of the goods. If tetramethylammonium hydroxide is used it decomposes upon heating into methyl alcohol and trimethylamine. The 85 other compounds of this type when they break up yield the tertiary base and the homologous bases, olefine and water.

The invention thus materially reduces the 90 after treatment required in connection with vat dyeing. In addition it saves time and equipment.

While we have herein disclosed a typical method of procedure, it will be understood 95 that the invention may be practiced in a variety of ways without departing from the spirit or scope thereof.

Having thus described our invention, what we desire to claim as new is:

1. That improvement in methods of vat 100

dyeing fabrics which consists in dyeing the goods in a dye bath made alkaline by the addition of a suitable quantity of a quaternary ammonium base, and subsequently, 5 while the goods still contain a considerable percentage of said bath, drying the goods at a temperature serving to decompose said base.

2. That improvement in methods of vat 10 dyeing fabrics which consists in dyeing the goods in a dye bath made alkaline by the addition of a suitable quantity of a quaternary ammonium base, squeezing out the surplus dye bath, and subsequently drying the 15 goods at a temperature serving to decompose said base.

3. That improvement in methods of vat 20 dyeing fabrics which consists in dyeing the goods in a bath containing a solution of the dye, a reducing agent, and an alkaline material which will break down into volatile constituents upon heating and subsequently drying the fabric at a temperature sufficient 25 to decompose said alkaline material.

4. That improvement in methods of vat 30 dyeing fabrics which consists in dyeing the goods in a bath containing a solution of the dye, a reducing agent, and a quaternary ammonium base.

5. That improvement in methods of vat 35 dyeing fabrics which consists in dyeing the goods in a bath containing a solution of the dye, a reducing agent, and a quaternary ammonium base, and subsequently drying the fabric under conditions which decompose said base.

6. A vat dye bath containing suitable 40 proportions of a vat dye, a reducing agent, and an alkali adapted to break down under moderate heat into constituents harmless to the goods.

7. A vat dye bath containing suitable 45 proportions of a vat dye, a reducing agent, and an alkali, the alkali being adapted to decompose into volatile constituents when heated to moderate temperatures.

8. A vat dye bath containing suitable proportions of a dye, a reducing agent, and a quaternary ammonium base.

50 In testimony whereof we have hereunto signed our names to this specification.

RICHARD G. KNOWLAND.
NATHANIEL KOSAK.

CERTIFICATE OF CORRECTION.

Patent No. 1,805,098.

Granted May 12, 1931, to

RICHARD G. KNOWLAND ET AL.

It is hereby certified that error appears in the printed specification of the above numbered patent requiring correction as follows: Page 1, line 35, for the misspelled word "tetramethylammonium" read tetraethylammonium; and that the said Letters Patent should be read with this correction therein that the same may conform to the record of the case in the Patent Office.

Signed and sealed this 7th day of July, A. D. 1931.
